ROY J. TAYLOR, OF ASHTABULA, OHIO, ASSIGNOR OF ONE-HALF TO THE AMERICAN GYPSUM CO., OF PORT CLINTON, OHIO, A CORPORATION OF OHIO

FASTENING CLIP FOR APPLYING PLASTIC LATH OR THE LIKE TO WOOD STUDDING

Application filed March 28, 1931. Serial No. 525,926.

This invention relates to fastening clips for applying plastic lath or the like to wood studding.

In applying this type of lath to the wood studding it is important that the fastening means be such that the lath is firmly secured to the studding.

Under prevailing methods these sheet rock or plastic lath strips are fastened to the studding or joists by the use of ordinary nails. These strips of lath are of an average size of 18 x 4", and to fasten such a strip to the joists or studding requires approximately from 30 to 40 nails. Four of my clips will 10 fasten the same strip with a considerable saving in time and labor.

Another advantage in the use of the clip is, that it helps in a material way to prevent the cracking of the plaster after it is applied 20 to the sheet rock lath, due to the fact that the clip is so constructed that when driven in the joist or studding it retains a certain amount of flexibility and prevents cracking of plaster even though the joists or studding 25 may shrink or settle.

The saving of time and labor by the use of the clip is another important advantage.

The above, and other features and advantages will more fully appear from the following specification, reference being had to the accompanying drawing, in which:

Figure 1 is a front elevational view of a fragmentary portion of a plurality of sheet rock lath secured to the vertical studs with the metal clips; Fig. 2 is a side elevation of the clip; Fig. 3 is a top plan view of Fig. 2; Fig. 4 is a front elevation; Fig. 5 is a fragmentary perspective view showing the manner in which the invention is used.

Referring to the drawing:—The upright studs are indicated at 10, the sheet rock lath at 11 and 11a, and a clip having a flat top plate 12 with down turned ends 13 and 14, and prong 15 with rib 16, said prong 15 40 being at a right angle to the top 12, and depending from a lateral extension 12a at one side edge of the top 12.

The prong 15 is inserted between the joining plaster boards or sheet rock laths 11 and 50 11a and driven or hammered firmly into the

stud 10, and the down turned ends 13 and 14 then lap or press down on the plaster boards or sheet rock sections 11 and 11a. The rib 16 in the prong portion 15 is for the purpose of reinforcement of the prong member. The 55 use of this clip allows a slight shifting of the plaster board as the studding shrinks or settles, but prevents the usual cracking of plaster.

The plaster board or sheet rock lath 11 60 and 11a may be fastened by the clips at a plurality of points along the studding 10.

A corner clip may be made by bending the end 14 up at right angles to the top surface 12 as shown in dotted line in Fig. 2. 65

The sheet metal of which the clip is made, and the angle where the prong 15 joins the plate, permits the clip to flex or bend slightly as the studding shrinks or settles, without cracking the plaster or disturbing the lathing 70 sufficiently to do so. The cracking of plaster on nailed lathing of this kind has been noticeable and objectionable.

The exact form of the fastener or clip may be varied within the scope of the invention. 75

I claim:

1. A fastener comprising an elongated sheet metal plate having an extension at one side edge spaced from each end thereof, and a pointed prong bent from one side edge of 80 said extension at an angle to the plane of the plate and at a right angle to the length of the plate, and adapted to be driven into a stud or the like.

2. A fastener comprising an elongated 85 sheet metal plate having an extension at one side edge spaced from each end thereof, and a pointed prong bent from one side edge of 90 said extension at an angle to the plane of the plate and at a right angle to the length of the plate, and adapted to be driven into a stud or the like, the opposite ends of the plate being bent down below the plane thereof.

In testimony whereof, I do affix my signature. 95

ROY J. TAYLOR.
